PLATE

Hans Hacker, East Liverpool, Ohio, assignor to
The Edwin M. Knowles China Company,
Newell, W. Va.

Application December 1, 1948, Serial No. 149,897

Term of patent 14 years

(Cl. D44—15)

To all whom it may concern:

Be it known that I, Hans Hacker, a citizen of Germany and a declarant alien under United States naturalization laws, residing at 330 Vine Street, East Liverpool, Ohio, have invented a new, original, and ornamental Design for a Plate, of which the following is a specification, reference being had to the accompanying drawing, forming a part hereof.

The sole figure of the drawing is a top plan view of a plate showing my new design. The dominant features thereof reside in the floral surface decoration as shown.

I claim:

The ornamental design for a plate, as shown and described.

HANS HACKER.
